UNITED STATES PATENT OFFICE.

PETER J. VEHLEN, OF MICHIGAN CITY, INDIANA.

NECK-YOKE.

SPECIFICATION forming part of Letters Patent No. 226,134, dated March 30, 1880.

Application filed January 15, 1880.

To all whom it may concern:

Be it known that I, PETER J. VEHLEN, of Michigan City, in the county of La Porte and State of Indiana, have invented certain new 5 and useful Improvements in Neck-Yokes, of which the following is a specification.

The object I have in view is to produce means for connecting the neck-yokes of carriages and wagons with the breast-straps which 10 will be strong, cheap, and simple, will strengthen instead of weaken the ends of the yoke-bar, and will allow the breast-straps to play easily upon the yoke bar without being rapidly worn thereby; and my invention therein consists in the construction, arrangement, and 15 combination of the parts composing my device, as fully hereinafter explained.

In the accompanying drawings, forming a part hereof, Figure 1 is a perspective view of 20 one end of a neck-yoke bar with my device for connecting the same with the breast-strap secured thereto; Fig. 2, a sectional view of the same lengthwise of the yoke-bar; and Fig. 3, a separate view, in section, of a part of the roller-loop.

Like letters denote corresponding parts in 25 all three figures.

A is a neck-yoke bar, made of wood, as usual, and having its ends tapered somewhat. 30 Upon each end of the yoke-bar is placed a metal plate or strap, B, having flat ends b, which set into recesses a, formed in the yoke-bar to receive them, and also having its central portion rounded and bent outwardly to 35 form an eye, c. This eye plate or strap is held upon the end of the yoke-bar by two metal bands or sleeves, C D, which are pushed over the ends of the strap, and are prevented from slipping off by screws or rivets d, which pass

through holes in the bands and in the ends of 40 the eye-strap.

By securing the eye-strap in this manner to the yoke-bar said bar is strengthened instead of being weakened, as is the case when a staple is used, and there is no tendency to split 45 the bar by the strain upon the eye in use.

Before being secured the eye-strap is passed through the roller-loop E, which is a loop made of metal. This loop is about the size of the eye at the end connected with such eye, but 50 its sides spread out toward the other end, where it has a straight round end bar, e, made of nearly the same size as the rest of the loop, so as to give the requisite strength. Upon this end bar is a shell-roller, F, which is prevented from playing endwise by shoulders f. The breast-strap passes through the loop E around the roller F, and can play back and forth through such loop with very little friction, and without the liability of being rapidly 60 worn and becoming weakened.

The whole device is very strong and simple, and is cheap to manufacture.

What I claim as my invention is—

1. The combination, with a neck-yoke bar, 65 of the eye-strap B, secured to its side, one at each end thereof, by metal bands C D, constructed and arranged substantially as described and shown.
2. The combination, with a neck-yoke bar, 70 of the eye-strap B, bands C D, loop E, and roller F, constructed and arranged substantially as described and shown.

PETER J. VEHLEN.
